UNITED STATES PATENT OFFICE.

CORY O. HUNTINGTON, OF CENTRALIA, WASHINGTON, ASSIGNOR OF ONE-HALF TO
GEORGE G. SEELY, OF PORTLAND, OREGON.

MILL-DOG FOR HEAD-BLOCKS.

1,105,328.

Specification of Letters Patent.

Patented July 28, 1914.

Application filed June 19, 1913. Serial No. 774,565.

To all whom it may concern:

Be it known that I, CORY O. HUNTINGTON, a citizen of the United States, residing at Centralia, in the county of Lewis and State of Washington, have invented certain new and useful Improvements in Mill-Dogs for Head-Blocks, of which the following is a specification.

My invention relates to mill dogs for head blocks, and has for its object to provide an improved means for holding dogs upon saw mill carriages.

A further object is to provide a series of eccentric levers for operating mill dogs to engage and hold the dog in place.

These and other objects will appear from a description of the structure shown in the accompanying drawing, in which—

Figure 1 is a side elevation showing the eccentric levers in working position. Fig. 2 is an edge view of the same. Fig. 3 is a detail view of a key for clamping the dog upon the upright. Fig. 4 is a detail view in perspective, showing the operative mechanism for the under dog.

Describing the drawing in detail, 1 is the upright lever secured upon the straps 4 of the eccentric disk 5 which is mounted upon the shaft 10 which passes through the stand 15 and has at its outer end an adjustable support 10^a. Over the eccentric disk and strap is secured the fork 6 of the lever 18, which fork is mounted upon the shaft 10 and fixed by means of bolt 19 to the disk 5 so that they will move together upon said shaft. The arms of the fork extend across the strap and prevent lateral movement thereof on the disk. 9 is a stop member projecting from the lower side of the straps 4 adapted to strike upon the base 16 and thus limit the movement of the straps. 7 is a weighted lever eccentrically mounted in the bracket 12 which is slidably secured upon the bar 8 fixed upon said disk, which is formed preferably on the arc of a circle.

Upon the shaft 10 at the outer side of the fork is slidably mounted, by means of the slot 11^b, the under dog 11 which has the forwardly and upwardly projecting pointed arm 11^b adapted to engage the lower portion of a log and the rearwardly extending portion 11^a which passes through the aperture 12^a of the bracket 12, and to which is fixed the right angled terminal 11^c. It will be seen that the dog 11 will be readily adjust-

able longitudinally in the bracket 12 and upon the shaft 10. The bracket also is freely movable upon the bar 8 until it is locked thereon by means of the lever 7 bearing upon the key 13, held in place by lugs 13^a. In 60 this manner the dog is adjustable to any size and position of the log upon the carriage blocks 16.

The upper dog 2 is slidably secured upon the upright 1, and over an open side thereof, in the bearing lugs 20, is mounted the eccentric lever 3. Beneath the eccentric and bearing upon the bar 1, is loosely held the key 14, by means of the lugs 21. When the dog is moved to the desired point, the 70 lever 3 will be dropped and its weight will securely lock the dog in place.

In the upper end of the fork is slidably secured a key 22 and upon it is adapted to bear the eccentric 23 of the lever 24 which 75 is mounted upon the lever 18 to form a brake or safety lock for preventing relative movement between the eccentric and straps. This prevents the lever 18 from dropping back upon the block 16 when not in operation; and it prevents the forward movement thereof against bar 1 when the under dog is carrying the weight of a log.

In operation the log 17 will be placed upon the block 16 and the upper dog 2 85 moved down to engagement therewith, when it will be locked by dropping the lever 3. The lever 18 will stand normally in vertical position as seen in Fig. 1, and the under dog will be thrust forward against the log and 90 locked by the lever 7. Now, upon releasing lever 24 the lever 18 will be thrown back, shifting the disk 5 in the eccentric strap. This movement will have the effect to draw the upright bar 1 downwardly forcing the 95 dog 2 into the log 17; and at the same time dog 11 will be raised and forced into the log from below. By reversing the movement of the lever, the dogs may be moved from each other; and the lever and upright may 100 be moved together on the central shaft.

Having thus described my invention so that others skilled in the art to which it pertains may make and use the same, what I claim as new and desire to secure by Letters Patent, is—

1. In a mill dog, a base, an eccentric disk mounted thereon, an eccentric strap cooperating with the disk, an upright lever fixed upon said strap, a dog secured thereon, a 110

dog mounted upon the disk in coöperative relation thereto; and a lever secured to the disk for rocking it, to effect vertical movement of said dogs.

5. In a mill dog, a base, an eccentric disk mounted thereon, an eccentric strap coöperating with the disk, an upright lever fixed upon the said strap, a dog secured thereon, a dog mounted for horizontal adjustment 10 on said disk in coöperative relation to the first mentioned dog and a lever fixed to the disk for rocking it to effect vertical movement of the dogs.

3. In a mill dog, a base, an eccentric disk mounted thereon, an eccentric strap coöperating with the disk, an upright lever fixed upon the said strap, a dog secured thereon, a dog mounted for horizontal adjustment 15 on said disk in coöperative relation to the first mentioned dog, a lever fixed to the disk for rocking it to effect vertical movement of the dogs, and means for varying the angle of the second mentioned dog.

4. In a mill dog, a base, an eccentric disk 20 mounted thereon, an eccentric strap coöperating therewith, an upright lever fixed to said strap, a dog slidably secured on the upright, a dog opposed thereto and adapted

to be secured in fixed relation upon the disk, and a forked lever encompassing the strap 30 and disk and rigidly fixed to the disk to prevent lateral relative movement and for effecting vertical movement of said dogs.

5. In a mill dog, a base, a shaft fixed transversely therein, an eccentric mounted 35 upon said shaft, an eccentric strap coöperating therewith, an upright carrying an upper dog, secured to the eccentric strap at the narrow side of the eccentric disk, a lever fixed to the disk, a guide bar secured upon 40 the disk at the broad side thereof, a bracket movable upon said bar and adapted to be locked at any desired point thereon, and an under dog slidably mounted upon said shaft and movable through an aperture in said 45 bracket, whereby the relative angle and longitudinal position of the lower dog may be varied and by shifting said lever, the dogs may be moved toward or from each other.

In testimony whereof I affix my signature 50 in presence of two witnesses.

CORY O. HUNTINGTON.
